SIGNAL LIGHT

Jefferson C. Gibson, 217 E. Cullerton Ave., Chicago, Ill.

Filed June 6, 1962, Ser. No. 70,440

Term of patent 14 years

(Cl. D72—1)

Fig. 1.

Fig. 2

Fig. 3

FIG. 1 is a front elevational view of a signal light showing my new design.

FIG. 2 is a top view of same;

FIG. 3 is a bottom view of same;

FIG. 4 is a side view of same;

FIG. 5 is a fragmentary sectional view as seen along line 5—5 in FIG. 2; and

FIG. 6 is a fragmentary sectional view as seen along line 6—6 in FIG. 3.

The rear of the signal light is substantially flat and plain. The dominant features of my design reside in the portions shown in full lines.

I claim:

The ornamental design for a signal light, as shown and described.
